UNITED STATES PATENT OFFICE.

WILLIAM C. BURMEISTER AND EDWIN N. SMOCK, OF CHICAGO, ILLINOIS, ASSIGNEES
OF ONE-HALF TO SAID BURMEISTER AND ONE-HALF TO SAID SMOCK.

WINDOW-HEATER.

1,243,703.

Specification of Letters Patent. Patented Oct. 23, 1917.

Application filed July 21, 1916. Serial No. 110,510.

To all whom it may concern:

Be it known that we, WILLIAM C. BURMEISTER and EDWIN N. SMOCK, citizens of the United States, and residents of Chicago, county of Cook, and State of Illinois, have invented a new, useful, and Improved Window-Heater, of which the following is a full, clear, true, and exact description.

Our invention relates to means for heating windows, and has particular reference to means for heating the windows, or windshields which protect the drivers of vehicles.

The object of our invention is to heat a vehicle driver's protecting window to prevent the accumulation thereon of moisture, sleet, snow or ice, and thus preserve said window in a clear condition for observation by the driver.

20 A further object of our invention is to provide a device by means of which the heat generated will be applied directly to the window to be heated in an efficient and economical manner, to provide a device 25 which can be easily applied, which shall be adapted for direct contact with the glass of the window, by means of which heat shall be applied to the glass to be heated both by direct radiation and by conduction, and by 30 means of which heat can be applied from a source of electrical energy.

A further object of our invention is to provide a device of the kind described which can be placed in position against the 35 glass, when needed, or swung out of such position when not needed, which shall automatically force itself into proper heat-conducting contact when positioned for use, and which shall be adapted to heat the portion of the window required, and shall be 40 arranged to obscure but a minimum portion of the glass when in operating position.

Our invention consists in a device for applying heat to a window, which device is 45 adapted for direct contact with the inner face of the glass, and which carries within itself means for generating heat.

Our invention also consists in an electric heating device adapted to be applied to the 50 inner surface of a motorman's window and mounted for movement toward and away from the window, provided with a flat contacting face and means for causing said flat face to evenly contact with the glass.

Our invention also consists in the several 55 features of construction and in the arrangements and combinations of parts whereby we are enabled to attain the above-mentioned and other objects and all as herein-after described and particularly pointed out 60 in the appended claims.

Our invention will be more readily understood by reference to the accompanying drawings forming part of this specification and in which:—

Figure —1— is a vertical sectional view 65 of our window-heating device as applied to a motor-man's window on an electric street car, or the like;

Fig. —2— is a fragmentary horizontal 70 sectional view on the line 2—2 of Fig. —1—;

Fig. —3— is a detail vertical section on the line 3—3 of Fig. —2—;

Fig. —4— is a detail vertical section on the line 4—4 of Fig. —1—;

Fig. —5— is a fragmentary vertical section on the line 5—5 of Fig. —2—;

Fig. —6— is a fragmentary rear elevation of an automobile wind shield showing the application of our invention thereto;

Fig. —7— is a vertical section of a wind- 80 shield and one of our heating devices showing a different means of mounting same; and

Fig. 8, is a fragmentary horizontal sec- 85 tion on the line 8—8 of Fig. —1—.

In said drawings 1 represents the motorman's window of a street car or similar vehicle. Above the window and secured to the wall of the car we arrange a box 2, in which we mount our heating device, and in which this form of our device is adapted to be stored when not in use. The box has a hinged cover 3 and may, of course, be locked if desired.

95 This form of our device comprises an elongated closed sheet metal casing 4 provided with a flat smooth surface 5 on one side for contact with the glass 1. Said flat side consists of perforated sheet metal and its longitudinal edges are turned over forming grooves 6 for receiving outwardly engaging flanges 7 formed on the casing, and by means of which the perforated side is removably held in place.

100 Upon one end wall we mount an elongated incandescent lamp 8 connected with a source of supply of electricity for producing the

heat which we utilize in heating the window. We preferably form the casing with a rounded or cylindrical back which serves to reflect the heat which strikes same toward the 5 front of the casing. Some of the heat produced by the lamp 8 is impinged directly against the glass through the perforations in the front plate 5 and some directly against the solid parts of the plate, furthermore the 10 whole casing is more or less heated by the lamps and as the perforated front is in close metallic contact with the main part of the casing the heat passes to the front by conduction, as naturally the front is continually cooled faster than the body of the casing 15 by reason of its contact with the glass.

For holding the casing in place we mount the casing on a swinging arm 9 connecting the arm to the casing at the rear side and 20 midway between its ends, by means of a universal joint connection 10, so that when the casing is pressed against the glass it will automatically accommodate itself to any slight lack of proper alinement and be set 25 into flat and firm contact with the glass throughout the area of its contacting surface.

The arm 9 is hollow and serves as a conduit for the electric wires 10^a for entering the 30 casing. The arm 9 is rigidly mounted at its opposite end on a horizontal pivot or shaft 11 carried in suitable fixed brackets or bearings 12. The arm can swing up and down on said shaft 11 from operative position, shown in full lines, Fig. —1—, to the inoperative position shown in dotted lines. For the purpose of holding the arm with the casing in its two positions we provide an arm 13 secured to one end of the shaft 11, 35 the free end of the arm being connected to one end of a tension spring 14, the opposite end of the spring 14 being secured to one wall of the box 2. The relations of said spring 14, arm 13 and main arm 9 are such 40 that the spring holds the casing against the glass with a yielding pressure and also when the casing is within the box holds the device in non-rattling condition.

The universal joint 10 comprises a hollow 50 ball-like member 15 rigid with the casing, and a spherical shell 16 formed on the end of the arm 9. The shell 16 and arm 9 are split as shown to permit the ball 15 to be entered into place and the two parts of the 55 shell are held together by suitable clamping bolts 17. The bolts 17 are tightened sufficiently to hold the ball 15 in place, but not so tight as to prevent the casing properly setting itself against the glass. The forward 60 edge 18 of the shell 16 is spaced from the back of the casing sufficient to permit necessary tilting of the casing to permit its flat contact with the glass.

The long narrow form of the casing permits its installation and use without en-

croaching upon that portion of the glass through which the motor-man wishes to look while operating the car.

In the form of our device which is particularly adapted for use on automobiles 70 we prefer to install the device permanently in contact with the glass and for this purpose we provide a rigid tubular arm 19 rising from the casing and provided at its upper end with means for securing it to 75 the frame of a wind-shield. When the frame is metal as 20 Fig. —7— this securing means is a clamp comprising a plate 21 formed to fit the frame 20 and to receive the clamping bolt 22, the upper end of the arm 80 19 being formed to coöperate with the plate 21 to clamp the device in position.

Where the wind-shield frame is of wood as 23, Fig. —6— the plate 21 and clamping bolt 22 are eliminated and the upper end of 85 the tube 19, which is flat, as shown, is secured directly to the frame by screws 24. In this form of our device the tube 19 serves as a conduit for the supply wires 10^a. In setting the heater upon a wind-shield it 90 is not difficult to form the free end 25 of the tube 19 so that the front face of the heater lies flat against the wind shield glass 26 in the best condition to most efficiently transmit the heat to the glass, and once the device has been installed, it remains permanently in position.

For permitting the lowering of the motor-man's window without the necessity of placing the heater within the box 2, we provide a 100 yielding support 27 secured to the bottom of the box 2 in the path of the arm 9. This support comprises two yielding or spring arms 28 secured together at one end and fastened to the box by screws 29. The body 105 parts of the spring members 28 are formed to provide a free space 30 in which to receive the arm 9 when the casing 4 is in contact with the glass 1. The free arms 28 of the spring members are deflected toward each 110 other at a point beyond the free space 30 to form shoulders 31 upon which the arm 9 may rest and hold the casing 4 out of contact with the glass and sufficiently removed therefrom to permit the lowering of the 115 window. The free ends 32 of the spring arms 28 are bent outwardly to form a flaring mouth to the space between the arms so that the arm can be easily forced between the arms thus spreading them apart against 120 their own resiliency and permitting the entrance of the arm to the free space 30 between the arms.

The spring 14 is not of sufficient strength 125 to force the arm 9 between the resilient arms 28 but a slight additional force is necessary. Once, however, the arm 9 has passed into the free space 30 the casing 4 is held in contact with the glass by the spring 14, and free of the yielding stop 27.

When the heater is in operation and an emergency should arise which requires the lowering of the motor-man's window, the motor-man simply pulls the heater away 5 from the window sufficiently to free the arm 9 from the yielding stop 27, and upon releasing the heater the arm 9 contacts with the outer end of the stop 27 and the heater is thus retained out of the path of the window.

10 We claim:

1. In an electric heater for windows, an elongated metallic casing, an electric heater within the casing, the casing having one flat 15 face for contact with a window, said flat face having a tongue and groove connection with the casing so that it can be easily removed to give access to the interior of the casing.
2. In an electric heater for windows, an elongated metallic casing, an electric heater within the casing, the casing having one flat 20 face for contact with a window, said flat face being uniformly perforated over its 25 whole extent to permit direct radiation therethrough in addition to the indirect radiation through the metal and said flat face being easily removable to give ready access to the interior of the casing.
3. In an electric heater for windows, an elongated metallic casing, an electric heater within the casing, the casing having one flat 30 face for contact with a window, said flat face being easily removable to give access to 35 the interior of the casing, and means for holding the casing with its flat face in contact with a window glass.
4. A window pane heater comprising a closed metallic casing having one flat easily 40 removable side for contact with a window pane, a heater within the casing, means for mounting the casing for movement from and toward a window pane, means for yieldingly holding the casing with its flat side in 45 contact with a window pane and means for temporarily holding the casing out of contact with the window pane a sufficient distance to permit the frame in which pane is held to pass said flat side.
5. A window heater comprising a closed 50 metallic casing, having a flat side for presentation to a window, an electric heater within the casing, a bent arm joined to the

rear of the casing at one end and mounted at its other end for swinging motion whereby the casing may be moved toward the window for heating same and away from the window for storage, and a spring for yieldingly holding the arm at both limits of its movement.

6. A window heater comprising a closed metallic casing, having a flat side for presentation to a window, an electric heater within the casing, a bent arm joined to the rear of the casing at one end by means of a universal joint, and said arm mounted at its other end for swinging motion whereby the casing may be moved into contact with the window for heating same and away from the window for storage, means for holding the casing in contact with the window pane with a yielding pressure, the universal joint permitting the casing to lie flat against the window pane regardless of any slight lack of alinement.

7. A window heater comprising a closed metallic casing, having a flat side for presentation to a window, an electric heater within the casing, a housing arranged near the window-pane, a bent arm mounted at one end within said housing and adapted to swing out of and into the housing, said casing mounted on the free end of the arm and adapted to be swung into contact with the glass and away from the window and into the housing, and yielding means for holding the arm at both limits of its movement.

8. A window heater comprising a closed metallic casing having a flat side for contact with a window pane, means for holding the heater yieldingly in contact with a window pane, an arm upon which the heater is secured for movement from and toward a window, and a yielding stop in the path of the arm to yieldingly hold the heater out of window contacting position.

In testimony whereof we have signed our names in presence of two subscribing witnesses.
